UNITED STATES PATENT OFFICE

GEORGE FREDERIC RIEGEL, OF NEW YORK, N. Y., ASSIGNOR TO PINAUD INCORPORATED, OF NEW YORK, N. Y., A CORPORATION OF NEW YORK

CARTON FOR DERMATOLOGICAL AND EPIDERMICAL CREAM

Application filed May 8, 1928. Serial No. 275,994.

This invention relates to a carton.

In preparing certain materials such as dermatological or epidermical creams for sale it is the practice to package them in deformable tubes which are then packed in cartons. These cartons are usually rectangular in cross section with the consequent result that when the usual deformable tube is used much space is wasted. Moreover, in the actual production of the carton much material is unnecessarily wasted.

The present invention contemplates a carton which is substantially triangular in cross section with the result that, when it is used to contain a tube of the character hereinbefore identified, much space will be economized and in the construction of the carton much material will be saved. At the same time there will be produced a distinctive carton which may be packed with the greatest economy of space.

In the drawings, there is illustrated one of the embodiments of the invention but, of course, the invention will not be restricted to this exact form, except as is necessitated by the claim.

Figure 1 is a perspective view of the carton;

Figure 2 is a cross sectional view;

Figure 3 is a longitudinal sectional view;

30 and

Figure 4 is a view of the blank after it is scored but before it is folded.

The form of the invention illustrated includes side walls 1, 2 and 3, the wall 1 being substantially wider than the walls 2 and 3, but all of the walls being of the same length.

One of the walls, 3 for instance, or it may be the remote wall 1, if desired, carries a flap 4 which is for the purpose of carrying an adhesive to secure the side walls in the triangular form. This flap may be of the desired form but in that shown the ends are beveled at 5 so that they will recede from the ends of the carton when it is in its assembled condition.

One of the other walls, 1 for instance, carries the ends 6 and 7, which are triangular in form, the edge 8 being co-extensive with the width of the side wall 1 and the edges 8 and 9

being co-extensive with the widths of the other walls 2 and 3.

Each of the ends 6 and 7 carries a tab 10 which projects from one side of the end by which it is carried in the direction of the next adjacent wall 2, and these tabs are so formed as to be easily insertable when the carton is assembled.

The remote wall 3 is also provided at its ends with tabs 11. One edge 12 of each of these tabs 11 is, in effect, an extension of the adjacent edge of the wall 3, while the other edge 13 is beveled. The reason for the particular formation of the edge 11 is that it forms when folded an abutment between 65 which and the wall 2 the tab 10 is held. The top and bottom or the ends of the carton are then held closed. Moreover, the tabs 11 reinforce the ends 6 and 7 and are held in contact with their inner faces by the contact with or 70 co-action of the tabs 10 and 11.

Of course, it is to be realized that the tabs 6 and 7 need not be carried by the edges 8 of the ends 6 and 7, but may be carried by the remote edges 9, in which event the tabs 11 75 will be carried by the walls 2.

In forming the carton, the blank is struck from a single piece of material and this blank includes the side walls, the ends and the tabs described. The side walls are defined by scoring along the lines 14 and 15. The ends are defined by scoring at 7 and the tabs 4, 10 and 11 by scoring at 16, 8 and 17 respectively.

The carton is formed by folding along the scoring 14 and 15 and the flap 4 is folded 85 along the scoring 16. The flap 4 is then located on the inner face of the wall 1 and secured thereto by any suitable means, such as an adhesive. The tabs 11 are then bent at right angles to the wall 3 and the ends bent along the scoring 7. The tabs 10 are then folded along the scoring 8 and forced inwardly between the edge 12 of the tabs 11 and the adjacent wall 2. The ends are then held 90 in position.

The carton is easy to assemble, saves packing space and material in making and, in addition, is of a novel, attractive and distinctive form.

What is claimed is:

In a carton, a blank formed to provide a triangular shaped carton, said blank having a body portion scored to form the sides of the carton, a flap extending from one side edge thereof, triangular portions extending from the end edges of one side portion of said carton, tabs extending from said triangular portions with the edge furthest from the body portion forming an acute angle with the edge from which they extend and tabs of substantially trapezoidal shape extending from the end edges of another side portion of said carton, the edges of said latter mentioned tabs forming angles with the end edges of said side portion equal to the angle formed between said side portion and the adjacent side portions when the carton is in folded position and adapted to hold the first mentioned tabs against the adjacent side portion when the carton is in folded position, all of the tabs being rounded at their free edges whereby the edges of the first mentioned tabs, which edges are adjacent to the body portion, are inserted into the carton, on folding, free from contact with the latter mentioned tabs.

In testimony whereof, I have signed my name to this specification this 2nd day of May, 1928.
